FUEL CONTROL SYSTEM

George R. Ericson, Kirkwood, and Irven E. Coffey,
St. Louis, Mo., assignors to Carter Carburetor
Corporation, St. Louis, Mo., a corporation of
Delaware

Application January 15, 1946, Serial No. 641,208

17 Claims. (Cl. 123—179)

1

This invention relates to charge forming devices for internal combustion engines.

Fuels, such as propane and butane, which are gaseous at normal atmospheric pressures and temperatures, are usually stored in highly compressed or liquid form.

A charge forming device for use with such highly volatile fuels must properly pressure and meter the fuel as well as prevent leakage when the engine is not in operation. Where the fuel is to be drawn through the carburetor by engine suction, the problem is increased because of the high volatility thereof.

Accordingly, the main object of the present invention is to provide an engine charge forming device constructed to efficiently utilize highly volatile or gaseous fuels.

Another object is to provide adequate safety means for preventing escape of the gas when the engine is not in operation.

Another object is to provide means for metering highly volatile fuel in accordance with engine suction.

Another object is to supply fuel for starting under conditions when there is insufficient suction available for causing the delivery of fuel by induction through the main fuel supply passage.

Another object is to provide novel means for enriching the fuel mixture during acceleration which means is especially adapted for use with highly volatile fuels.

Still another object is to provide novel means for controlling the air supply to the carburetor particularly during starting.

These objects and other more detailed objects hereafter appearing are obtained by the devices illustrated in the accompanying drawings in which

Fig. 1 is a diagrammatic view showing parts of internal combustion engine fuel and electrical systems embodying the invention.

Fig. 2 is a similar view showing a modification.

Figs. 3 and 4 are similar views showing still other modifications.

Fig. 1 shows a downdraft carburetor having a mixture conduit 5 provided with a central Venturi tube 6 and a throttle valve 7. The mixture conduit is mounted on the engine intake manifold 8 in the usual manner and forms a part of the engine intake system. Adjacent the mixture conduit there is provided a pressure reducing and heating device 9 which comprises a casing forming chambers 10 and 10a separated by a horizontal diaphragm 11. A stationary needle 12 car-

2

ried by the upper part of the casing controls a central passage 13 in the diaphragm. The diaphragm is urged upwardly by a coiled spring 14 so as to normally close port 13. Upper chamber 5 10 is connected by a tube 15 to a tank 16 containing a supply of highly compressed fuel such as propane or butane.

Fuel at a much lower pressure is delivered through the passage 18 connected to lower chamber 10a. In order to counter-act the cooling effect caused by expansion of gases passing through port 13, a coiled tube 19 is mounted in chamber 10a for exposing expanded gases to a heating medium such as exhaust or hot water. A somewhat similar pressure reducing and heating device is disclosed and claimed in a co-pending application in the name of Irven E. Coffey, Serial No. 641,207, filed January 15, 1946, and assigned to the assignee of the present application.

20 A chamber 20 connected with passage 18 has a valve seat port 21 at its upper extremity controlled by a conical valve 22. This valve has a stem 23 connected to a diaphragm 24 mounted in a chamber 25 communicating with chamber 25 20 through port 21. A coiled spring 26 urges diaphragm 24 upwardly and normally maintains valve 22 closed.

A passage 28 leads from chamber 25 and has branches 29 and 30. Main fuel supply branch 30 29 discharges into the mixture conduit through an annulus 31 and ports 32 in the throat of Venturi tube 6. Passage 30 discharges through idling ports 33 located adjacent and slightly posterior to the throttle when closed. Branches 35 29 and 30 are provided with check valves 34 and 35 opening toward their respective discharge ports so that when dominant suction exists in one branch, the other branch will be closed by its respective check valve. Branch 30 serves for supplying idling fuel to the engine whereas branch 29 delivers the main fuel supply. Idling branch 30 is provided with an air bleed 36 and an economizer restriction 37.

An auxiliary passage 40 connects passage 18 45 below or anterior to chamber 20 to a valve chamber 41 through a valve seat port 42 and passes through a duct 43 to idling fuel branch 30. Port 42 is controlled by a valve 44 formed as the armature of a solenoid coil 45 and is normally urged closed by a coiled spring 46. The solenoid coil is connected through one blade of double pole switch 47 to ground and through ignition switch 48 and lead 49 to battery 50. The arrangement is such that when both 55 the ignition switch and the double pole switch

are closed, the solenoid will be energized and valve 44 opened to permit the delivery of starting fuel through passage 43 and idle ports 33. The other pole of switch 47 connects battery lead 49 to starter motor 51. Throttle 7, preferably, will be partly opened during starting.

In order to insure closing of main fuel metering valve 22 when the engine is not in operation, even though spring 26 or diaphragm 24 may be damaged, an additional spring 55 within chamber 20 bears against the head portion 56 of a stem 57 projecting from the armature 58 of a solenoid 59. The solenoid is connected to ground, as at 60 and through ignition switch 48 to battery lead 49. When the ignition is turned on, armature 58 and head element 56 will be drawn downwardly by the solenoid to compress spring 55 and permit opening of valve 22 under the influence of engine suction applied through the induction conduit and passage 28 to diaphragm 24.

Formed on the upper side of diaphragm 24 is a dash pot chamber 65 in which works a rather close fitting piston 66 forming an upper movable wall for the chamber, the chamber being provided with an air bleed 67 for charging the same with air. Diaphragm 24 forms a lower movable wall for the chamber. A yoke 68 connected to the diaphragm slidably receives a lateral element 69 on a rod 70 carried by piston 66. A second rod 71 is pivoted to the piston and to a lever 72, itself pivotally carried at 73 by the short arm 74 of a bell crank. Lever 72 at its opposite extremity is connected by a link 75 to an arm 76 mounted on the throttle shaft and rigidly movable therewith. The bell crank is permanently pivoted at 77 and has a long arm 78 connected by a link 79 to a piston 80 working in a cylinder 81 connected by a passage 82 to intake conduit 8 posterior to the throttle. This arrangement is such that upon increase of suction in manifold 8, bell crank 74, arm 78 is rotated counter-clockwise to lift lever pivot 73 and, through yoke 68, to lift diaphragm 24 and move valve 22 towards its closed position. A coiled spring 83 in cylinder 81 normally urges piston 80 upwardly in a direction to lower pivot 73 and piston 66 and permit additional opening of valve 22.

In operation, when the ignition and starter switches are both closed, main metering valve 22 will be released by safety solenoid 59 and auxiliary valve 44 will also be opened by solenoid 45. Ordinarily there will be insufficient suction transmitted through passage 28 to affect diaphragm 24 and metering valve 22 during cranking. However, a sufficient supply of fuel for starting will be delivered through auxiliary passage 40 and idle ports 33. When the engine starts to run under its own power, starting switch 47 will be opened, de-energizing solenoid 45 and permitting closing of valve 44. Thereafter, the fuel, which is fully gasified and sufficiently reduced in pressure, preferably below atmospheric, by the device 9, will be delivered by induction through one or the other of branch passages 29 and 30, in accordance with whether the throttle valve is opened or closed, and fuel will be metered by valve 22 in response to suction conditions in passage 28 and the mixture conduit. Piston 80 and cylinder 81 and connected parts constitute a suction economizer device which tends to lean out the mixture at high suction in the intake manifold.

In case the throttle valve is suddenly opened connection 11, 12, 75 causes piston 66 to be lowered and the air in cylinder 65 will be compressed.

so as to urge diaphragm 24 downwardly and momentarily increase the opening of valve 22. The air pressure in chamber 65 will gradually dissipate through air bleed 67 so that spring 26 returns the diaphragm and valve to its stable position. When the throttle valve is substantially fully opened, element 69 on link 70 will engage the upper extremity of stem 23 and positively open the valve to provide additional enrichment as long as the throttle remains in this position.

The form in Fig. 2 is similar to that in Fig. 1 but includes some additional elements. Located within a casing 90 mounted on tube 13 is a closed thermostat 91 having its outer end anchored to the casing and its inner end attached to a shaft 92 which rigidly mounts an arm 93. This arm is connected by a link 94 to an arm 95 which operates a valve 96 controlling the passage of heating fluid through the device 9. Thus the heating 20 of the expanded gas in member 9 is controlled by the temperature of the outgoing gas in passage 18.

Arm 93 is also connected by a second link 97 to a lever 98 having an eccentric extremity 99 which cooperates with a lip 100 on throttle operating lever 101 to variably limit the idling position of the throttle valve in accordance with temperature.

In Fig. 3, the auxiliary starting by-pass for fuel is omitted and a choke valve 105 is mounted off center on a shaft 106 in the upper part of mixture conduit 5a. A thermostatic bi-metallic coil 107 is mounted about the choke shaft so as to yieldingly close the choke valve when the temperature is low. This substantially reduces the air supply and increases the effective suction on the ports 32a available for drawing starting fuel through main fuel branch 29. A lever 108 rigid with the choke shaft is connected by a link 109 to a piston 110 which works in a cylinder 111 connected at its lower extremity by a passage 112 to chamber 25a and thence through passage 28 to the mixture conduit. A coiled spring 113 constantly urges piston 110 upwardly in a direction to close the choke. During the warm-up period the position of the choke fluctuates in accordance with the resistance of the thermostat which opposes the direct action of air flow on the choke and the action on piston 110 of suction transmitted through fuel passage branches 29 and 30. When the engine reaches normal temperature, thermostat 107 moves the choke valve to its wide open position and holds it there.

In Fig. 4, choke shaft 106a has a detent 115 formed rigid therewith outside the mixing conduit. An arm 116 rigid with the throttle shaft carries a link 117 which extends to the detent. This link is connected by a link 118 to a piston rod 119 and piston 120 working in a cylinder 121 connected by a passage 122 to the mixture conduit posterior to the throttle.

In operation, to start the engine, the throttle valve is moved to a partially opened position which, through link 117 and detent 115, closes the choke valve. When the engine starts to run under its own power, suction applied to piston 120 rotates link 117 to clear detent 115 so that, thereafter, the throttle and choke valves are free to move independently of each other.

The invention may be modified in various respects as will occur to those skilled in the art and the exclusive use of all modifications as come within the scope of the appended claims is contemplated.

We claim:

1. In combination with an internal combustion

5

engine having a starter and an induction conduit, a source of highly volatile fuel supply, passage means connecting said source to said conduit, a pair of valves controlling said passage means, a device operable responsive to suction conditions in said passage and conduit for opening one of said valves, and means operatively connecting said starter and said valve and actuatable upon operation of said starter for opening the other valve.

2. In combination with an internal combustion engine induction conduit having a throttle therein, a source of highly volatile fuel supply, passages connecting said source and said conduit and including a main fuel passage and an idling fuel passage discharging, respectively, anterior and posterior to said throttle when closed, a normally closed valve controlling each of said passages, a device responding to suction in said conduit for opening a first of said valves controlling the supply of fuel anterior to said throttle, a self-starter for the engine, and means operatively connecting said starter and the second valve controlling the supply of fuel posterior to said throttle and actuatable upon operation of said starter to start the engine for opening said second valve.

3. In combination with an internal combustion engine induction conduit having a throttle therein, a source of fuel supply, main and idling fuel passages connecting said source and said conduit, a valve controlling a supply of fuel to said idling passage, an engine starter, and means operatively connecting said starter and said valve and actuatable upon operation of said starter to start the engine to open said valve.

4. In combination with an internal combustion engine induction conduit having a throttle therein, a source of fuel supply, main and idling fuel passages connecting said source and said conduit, said idling passage discharging through a port located posterior to said throttle when closed, an additional passage connecting said source and said idling port for supplying starting fuel, a valve controlling said additional passage, an engine starter control, and means operatively connecting said starter and said valve and actuatable responsive to operation of said control for opening said valve.

5. In combination with an internal combustion engine induction conduit, fuel supply means, a passage connecting said supply means and said conduit, a valve controlling said passage, spring means urging said valve closed, a device responsive to suction conditions in said conduit for opening said valve, an engine ignition system, and means responsive to energizing of said system for positively counter-acting said spring means.

6. In combination with an internal combustion engine induction conduit, fuel supply means connected to said conduit, a normally closed valve controlling the supply of fuel to said conduit, an engine ignition switch, and means responsive to suction in said conduit and closing of said ignition switch for positively opening said valve.

7. In combination with an internal combustion engine induction conduit, a source of highly volatile fuel supply connected to said conduit, a normally closed valve controlling the supply of fuel to said conduit, a device responsive to suction conditions in said conduit for opening said valve, an engine ignition system, safety means for urging said valve closed, and means responsive to energizing of said system for overcoming said safety means.

6

8. In combination with an internal combustion engine induction conduit, a source of highly volatile fuel supply, fuel passages extending from said source to said conduit for supplying fuel for normal operation and also for starting, a valve controlling said normal fuel supply passage, an engine ignition system, means responsive to engine suction for opening said valve, safety means normally urging said valve closed, means operatively connecting said ignition system and said safety means and actuatable responsive to energizing of said ignition system for overcoming said safety means, a second normally closed valve in said starting fuel passage, an engine starter control, and means operatively connecting said starter control and said second valve and actuatable responsive to operation of said control for opening said second valve.

9. In combination with an internal combustion engine induction conduit having a throttle therein, supply means for highly volatile fuel, a passage connecting said supply means and said conduit, a valve controlling said passage, a first device operatively connected to said valve and said conduit and responsive to suction in said conduit to actuate said valve in an opening direction upon increase in suction in said conduit, and a second device operatively connected to said throttle and said first device to open said valve independent of the action of suction on said first device.

10. In combination with an internal combustion engine induction conduit having a throttle therein, passage means for supplying highly volatile fuel to said conduit, a valve in said passage means, and a fluid charged chamber having a pair of individually movable walls, one of said walls being operatively connected to said valve and the other wall being connected to said throttle and having a lost motion mechanical connection to said valve whereby actuation of said throttle and said second wall acts through the fluid in said chamber to yieldingly motivate said first wall and said valve and actuation of said throttle in the opposite direction positively shifts said valve.

11. In combination with an internal combustion engine induction conduit having a throttle, a source of highly volatile fuel, a passage connecting said source to said conduit, a valve controlling said passage, a chamber having a movable wall exposed to suction in said passage and connected to said valve for opening said valve, a dash pot chamber on the opposite side of said movable wall from said passage, a second movable wall for said dash pot chamber, and an operative connection between said throttle and said second movable wall whereby opening of said throttle actuates said second movable wall and yieldingly motivates said first movable wall and said valve, and further including a lost motion mechanical connection between said throttle and said valve for positively opening the latter responsive to substantially full opening of said throttle.

12. In combination with an internal combustion engine, induction conduit means of the engine, a fuel supply device operatively connected to said conduit means, a normally closed valve for said device controlling the supply of fuel to said conduit means, an engine ignition system including a switch means, and means including an operative connection between said several means and said valve responsive to suction in said conduit means and operation of said igni-

tion switch means, respectively, for opening said normally closed valve.

13. In a charge forming device for an internal combustion engine, a mixture conduit, fuel supply means, a passage connecting said source to said conduit, a valve controlling said passage, a throttle in said conduit, a resilient connection between said throttle and said valve for opening said valve when said throttle is opened, said resilient connection including a pivoted lever, and a device responsive to variations in suction posterior to said throttle for altering the position of the lever pivot and thereby affecting said valve.

14. The combination specified in claim 13 in which said resilient connection is formed by a dash pot device having a pair of movable walls, one being connected to said throttle and the other being connected to said valve.

15. The combination specified in claim 13 further including a movable wall exposed to suction conditions in said fuel supply passage for opening said valve.

16. In combination with an internal combustion engine induction conduit having a choke and a throttle, main and auxiliary fuel passages discharging respectively, anterior and posterior to said throttle, a valve controlling said auxiliary passage, an engine starter control, means operatively connecting said control and said valve and actuatable responsive to operation of said control for opening said valve, and thermostatic means for closing said choke for starting to provide sufficient suction in said conduit during cranking of the engine to draw starting fuel through said auxiliary passage.

17. In a charge forming device for an internal combustion engine, a mixture conduit having

5 choke and throttle valves, a fuel supply passage discharging into said conduit, an operative connection between said throttle and said choke valve for closing said choke valve when said throttle is partially opened, and means operatively connected with said conduit and actuatable responsive to engine suction when the engine is operating under its own power and operatively connected with said connection for disabling said operative connection.
